CLAIM

The ornamental design for a universal smartphone adapter, as shown and described.

DESCRIPTION

FIG. 1 is a front perspective view of a universal smartphone adapter showing my new design in a first configuration; FIG. 2 is a rear perspective view thereof; FIG. 3 is a front view thereof; FIG. 5 is a left side view thereof; FIG. 6 is a right side view thereof; FIG. 7 is a top view thereof; FIG. 8 is a bottom view thereof; FIG. 9 is a front perspective view of the universal smartphone adapter of FIG. 1 shown in a second configuration; FIG. 10 is a rear perspective view thereof; FIG. 11 is a front perspective view of the universal smartphone adapter of FIG. 1 shown in a third configuration; FIG. 12 is a rear perspective view thereof; FIG. 13 is a front perspective view of the universal smartphone adapter of FIG. 1 shown in a fourth configuration; FIG. 14 is a rear perspective view thereof; FIG. 15 is a front perspective view of the universal smartphone adapter of FIG. 1 shown in a fifth configuration; and, FIG. 16 is a rear perspective view thereof.

The broken lines in the drawings illustrate the portions of the universal smartphone adapter, which form no part of the claimed design.

1 Claim, 16 Drawing Sheets
